DOUBLE SUCTION PLUNGER

Filed April 16, 1945

FIG. 1.

INVENTOR.

Gust Bonde

BY

Kimmel & Crowell Atty's

UNITED STATES PATENT OFFICE

2,406,317

DOUBLE SUCTION PLUNGER

Gust Bende, Marinette, Wis.

Application April 16, 1945, Serial No. 588,615

2 Claims. (Cl. 4—255)

1

This invention relates to improvements in suction plungers for clearing clogged drains or the like.

An object of this invention is to provide an improved suction plunger which is simple in construction and will automatically return to its normal position, the device including inner and outer suction cups, said cups cooperating with each other to provide an efficient suction action for quickly cleaning or loosening drains in various types of fixtures.

Another object of this invention is to provide a device of this kind which, by reason of the novel construction thereof, is more powerful in its operation than conventional suction cups.

With the above and such other objects in view, as may hereinafter more fully appear, I have invented the device shown in the accompanying drawing, in which:

Figure 1 is a vertical section, partly broken away and in detail, of a suction pump constructed according to an embodiment of this invention.

Figure 2 is a sectional view taken on the line 2—2 of Figure 1.

Referring to the drawing, the numeral 10 designates generally an outer resilient cup member which is formed at the lower large open end thereof with a flange or rib 11. The cup member 10 is formed at the upper end thereof with a boss 12 having an opening 13 therethrough, the purpose for which will be hereinafter described.

An inner resilient cup member 14 is disposed within the outer cup member 10, and opens downwardly. The inner cup member 14 terminates at its lower open end adjacent the lower end of the outer cup member 10, and is secured to the inner side of the outer cup member 10, as indicated at 15.

The inner cup member 14 may be vulcanized or otherwise firmly secured to the outer cup member 10 so as to form substantially an integral bond. The inner cup member 14 is provided with an upwardly extending boss 16, and, as shown in Figure 1, when the device is in normal position the upper end of the inner cup member 14 will be disposed in downwardly spaced relation to the upper end of the outer cup member 10. The lower end of a plunger rod 17 is threaded into the boss 16, and slidably engages through the opening 13 of the boss 12.

A spring 18 is positioned about the plunger rod

2

17, bearing at its lower end against the upper end of the boss 12, and bearing at its upper end against a transversely extending pin 19 engaging through the rod 17.

5 In the use and operation of this device, the cup member 10 has the flange or rib 11 thereof engaged about the drain opening. The plunger rod 17 is then moved downwardly so as to flex and distort the inner cup member 14, as shown in dotted lines in Figure 1. Pressure in a downward direction on plunger rod 17 will compress the spring 18 so that the outer cup member 10 will be tensioned against the surface of the fixture about the opening. As the inner cup member 14 flexes downwardly the air inside of this member will be forced downwardly and this air will provide a force for unclogging the drain.

The plunger rod 17 may be worked up and down and as the plunger rod 17 is released the spring 18 will force this rod upwardly so as to return the inner cup member 14 to substantially its normal position. In this manner the pump will operate automatically on its return stroke and the downward pressure on the outer cup member 10 will provide sufficient pressure to seal the flange 11 about the drain opening.

20 The above is the preferred embodiment of my invention but it is to be understood that modifications may be resorted to that fall within the scope of the claimed invention.

25 What I claim is:

1. A suction plunger comprising a resilient outer cup having an opening and a boss about said opening, an inner cup secured at its lower end to said outer cup, said inner cup having an opening 30 aligning with the opening of said outer cup, and a plunger rod secured to said inner cup and slidably engaging through said first opening.

2. A suction plunger comprising a resilient outer cup having an opening and a boss about said opening, an inner cup secured at its lower end to said outer cup, said inner cup having an opening aligning with the opening of said outer cup, a plunger rod secured to said inner cup and slidably engaging through said first opening, a spring 35 about said rod bearing at one end against said boss, and a spring tensioning member fixed relative to said rod and bearing against the opposite end of said spring.

GUST BONDE.
